UNITED STATES PATENT OFFICE

169,029

ARTIFICIAL FISH LURE

Alberto A. Concepcion, Detroit, Mich.

Application November 16, 1951, Serial No. 17,438

Term of patent 14 years

(Cl. D31—4)

To all whom it may concern:

Be it known that I, Alberto A. Concepcion, a citizen of the United States, residing at Detroit, in the county of Wayne and State of Michigan, have invented a new, original, and ornamental Design for an Artificial Fish Lure, of which the following is a specification, reference being had to the accompanying drawing, forming part thereof.

Fig. 1 is a plan view of an artificial fish lure, showing my new design.

Fig. 2 is an edge view of the same.

I claim:

The ornamental design for an artificial fish lure, as shown.

ALBERTO A. CONCEPCION.
